ABSTRACT

An internal magnetic shield of generally truncated pyramidal shape conforming generally to the inner wall of the funnel of a rectangular shadow mask type color picture tube is made up of four pre-annealed trapezoidal pieces of magnetic sheet metal assembled and attached together by overlapping flanges integral with the non-parallel sides of the pieces. The larger end of the shield is attached to the shadow mask frame by integral flanges on the long sides of the trapezoidal pieces. The sheet metal of the shield is annealed either before or after being formed into the trapezoidal pieces, but before assembly and attachment of the pieces together.

METHOD OF MAKING CATHODE RAY TUBE INTERNAL SHIELDS

This is a division, of application Ser. No. 95,779, filed Dec. 7, 1970, now abandoned.

BACKGROUND OF THE INVENTION

The present invention relates to an improvement in cathode ray tubes, such as color picture tubes, wherein the position of the electron beam spot on the screen is critical, and is affected by stray magnetic fields in the beam path. For example, in a shadow mask type color tube wherein a plurality (usually three) of convergent electron beams are projected through a multi-apertured color selection shadow mask to a mosaic screen along beam paths such that each beam impinges upon and excites only one of the (three) kinds of color phosphor elements in the screen, the color phosphor elements are usually located on the faceplate during manufacture by a method (e.g., by photoprinting through the mask) which does not involve any magnetic field. Thus, when the finished tube is operated in the presence of a magnetic field, such as the earth's field, undesirable misregister of the beam spots and color phosphor elements is produced. For this reason, such color tubes, especially those with a high deflection angle (e.g., 110°), are sometimes provided with an internal magnetic shield mounted within the envelope funnel and extending along at least the forward half thereof nearest the mask and screen. Heretofore, such internal shields have been made in one piece by drawing a flat sheet of magnetic sheet metal, such as cold-rolled steel, into a frustum of a cone or pyramid to conform to the inner wall of the envelope funnel. Particularly in the case of rectangular tubes where the forward end of the funnel has the general shape of a truncated pyramid, this drawing operation work hardens the material and reduces its magnetic properties. For best magnetic properties, the shield should be thoroughly annealed after all forming operations are completed. However, the annealing of finished one-piece shields would require large separate stacking fixtures and a large annealing oven, which would be very expensive.

SUMMARY OF THE INVENTION

The internal magnetic shield in a cathode ray tube is made up of four pre-annealed trapezoidal pieces or plates of magnetic sheet metal assembled and attached together along the non-parallel sides thereof. Preferably, the non-parallel sides of each pair of adjacent pieces are attached to each other by means of overlapping flanges integral with the pieces, and the larger end of the shield is mounted on an electrode, e.g., a shadow mask frame in a color picture tube, in the envelope by means of integral flanges on the long sides of the trapezoidal pieces.

BRIEF DESCRIPTION OF THE DRAWING

FIG. 1 is a side view, partly in axial section on line 1-1 of FIG. 2, of a rectangular shadow mask color picture tube incorporating the present invention.

FIG. 2 is a front end view of the picture tube of FIG. 1.

FIG. 3 is a plan view of the four-piece magnetic shield of the present invention.

FIGS. 4 and 5 are side and end elevation views of the magnetic shield of FIG. 3.

For example, the present invention is illustrated in FIGS. 1 and 2 as incorporated in a rectangular color picture tube 1 comprising a glass envelope 3 including a panel 5, a funnel 7 and a neck 9. The funnel 7 comprises a small circular end joined to the neck 9 and a large end of generally truncated pyramidal shape frit sealed to the panel 5. The panel 5 comprises a generally rectangular faceplate 11 and a peripheral side wall 13. A mosaic color phosphor screen 15 is disposed on the inner surface of the faceplate 11. An electron gun structure 17 is mounted in the neck 9 to project three convergent electron beams toward the screen 15. The tube 1 is adapted to be used with a magnetic deflection yoke 19 for scanning the electron beams over the surface of the screen. A multi-apertured color selection shadow mask 21 is mounted in predetermined spaced relation adjacent to the screen 15. The mask 21 includes a mounting frame 23 comprising an axially-extending flange 25, to which an apertured masking member 27 is welded, and an inwardly-extending flange 29 which serves as an electron shield for intercepting the beam if it overscans the masking member 27 at maximum deflection, shown by the dashed lines 30 in FIG. 1. The mask frame 23 is mounted within the panel 5 by means of four leaf springs 31, each welded at one end to the frame (or an intermediate bi-metallic plate) and having a hole at the other end fitted over one of four metal studs 33 fixed to the side wall 13.

A four-piece magnetic shield 35 is disposed within the larger end of the funnel 7 and supported by the mask frame 23. The shield 35 is shown schematically only in FIGS. 1 and 2, and is shown in detail in FIGS. 3 to 5. The shield 35 has a generally truncated pyramidal shape, like the larger end of the funnel 7, and is made up of two pairs of pre-annealed trapezoidal pieces or plates 37 and 39, the two plates of each pair being identical. Each of the two plates 37 is formed along its non-parallel sides with integral flanges 41 which are bent at a suitable small angle to receive similar flanges 43 on the non-parallel sides of the adjacent plates 39, in overlapping relationship. After assembly of the four plates 37 and 39 as shown in FIG. 3, the overlapping flanges 41 and 43 are attached together, as by welding or riveting. The plates 37 and 39 are formed along their longer sides with integral flanges 45 and 47, respectively, bent to extend parallel to the longitudinal axis of the shield 35, as shown in FIGS. 4 and 5. The shield 35 is mounted on the mask frame 23 by telescoping the flanges 45 and 47 over the frame 23 and attaching the flanges to the frame, as by welding. The flanges 45 and 47 are formed with notches 49 to clear the mounting springs 31 (or attaching plates).

The plates 37 and 39 are cut from magnetic sheet metal, such as aluminum-killed-steel (AKS) having a thickness of 4 to 8 mils, and stamped to form the integral flanges 41, 43, 45 and 47. The formed plates are preferably annealed after the stamping operation. However, the sheet metal may be annealed before the plates are formed, since the small amount of bending involved in the formation of the flanges has only a small effect on the magnetic properties of the finished shield 35. The annealing can be done after the flanges are formed at a comparatively low cost, since the separate plates 37 and 39 are relatively flat, and hence, do not require a large annealing oven.

The presently planned use of the invention is in shadow mask color picture tubes, as described above. However, the improved magnetic shield can be used in other types of color picture tubes having mosaic screens, or in oscilloscope tubes, for example, in which the instantaneous position of the beam spot on the phosphor screen is critical.

I claim:

1. The method of making a funnel-shaped internal magnetic shield for a rectangular cathode ray tube having a funnel portion of generally truncated pyramidal shape, comprising the steps of:

a. forming two pairs of trapezoidal plates of magnetic sheet metal having dimensions such that when the

5

magnetic plates are assembled together with their non-parallel sides fitted together they will form a truncated pyramid similar to the inner wall of said funnel portion;

b. annealing said trapezoidal plates to optimize the magnetic properties; and

c. then assembling said plates together as recited in *a* and attaching said non-parallel sides of adjacent plates to each other.

10 2. The method of claim 1, wherein each of said plates is formed in step *a* with integral flanges on said nonparallel sides, adapted to overlap the flanges of the adjacent plates when assembled together.
